DESIGN FOR A BOOK HOLDER OR ANALOGOUS ARTICLE

Ethel Dupont Heausler, New Orleans, La.

Application April 10, 1941, Serial No. 100,306

Term of patent 14 years

To all whom it may concern:

Be it known that I, Ethel Dupont Heausler, a citizen of the United States, residing at New Orleans, in the parish of Orleans and State of Louisiana, have invented a new, original, and ornamental Design for a Book Holder or Analogous Article, of which the following is a specification, reference being had to the accompanying drawing, forming part thereof.

In the drawing, the single view is a perspective of a book holder or analogous article, showing my new design.

I claim:

The ornamental design for a book holder or analogous article, as shown,

ETHEL DUPONT HEAUSLER.
